(57) **CLAIM**

The ornamental design for the audio component with main control knob, as shown and described.

DESCRIPTION

FIG. 1 is a perspective view of the audio component with main control knob showing the new design.

FIG. 2 is a top plan view of the audio component with main control knob of FIG. 1.

FIG. 3 is a front elevational view of the audio component with main control knob of FIG. 1.

FIG. 4 is a bottom plan view of the audio component with main control knob of FIG. 1.

FIG. 5 is a back elevational view of the audio component with main control knob of FIG. 1.

FIG. 6 is a right-side elevational view of the audio component with main control knob of FIG. 1; and,

FIG. 7 is a left-side elevational view of the audio component with main control knob of FIG. 1.

The broken lines shown are included for the purpose of illustrating the unclaimed portions of the article and form no part of the claim.
